TELEPHONE SYSTEM

Application filed October 14, 1927, Serial No. 226,054, and in Austria January 25, 1927. Renewed May 3, 1930.

This invention relates to telephone systems in general, but is concerned more particularly with calls between an automatic private branch exchange and an automatic main exchange.

The object of the invention is to permit a private branch exchange subscriber, after being connected with a main exchange subscriber, to call another local private branch subscriber and then reestablish connection to the established main exchange connection without releasing the main exchange connection. The oldest arrangements for this object provide each station with two line connections which, however, has the drawback that both the set as well as the wiring system becomes costly. Therefore, it has been proposed to allot the means for bringing about the switching-over to the back-call, not to the subscriber, but to the exchange line. By this it is made possible that only one pair of speaking wires is necessary for the extension station. The energization of the switching member allotted to the central exchange line takes place mostly over a third wire or over earth, it being possible to give the impulse for switching either permanently or temporarily. In any case the call-back set requires special devices.

The present invention relates to a call-back system particularly for connecting to automatic house exchanges or private branch exchanges, wherein, for the house sets, the exchange sets, as well as for the call-back sets, the same simple type is used as is characteristic for a system working according to the loop system and the call-back device for private branch exchanges for switching over to a back call and also for switching back to the exchange call, is released by selecting impulses or by a similar operation. Preferably, a sequence switch carries out the necessary switching actions.

Fig. 1 shows an example of the invention and indicates a system for automatic traffic. Only those parts are shown which are essential for an understanding of the invention.

The automatic house exchange will be assumed as catering for 1,000 subscribers as a

maximum. The impulses are produced by interrupting the loop and the exchange lines are connected to the top level of the group selectors so that the hunting selection of an exchange line takes place through the group selector. The central exchange is assumed in the example as being an automatic exchange for 10,000 subscribers. The call-back devices are, of course, capable of adaptation to each exchange.

In the first place a back call with out-going traffic will be described.

The subscriber A takes up his receiver and thereby in known manner engages a group selector such as SEL over his preselector or line finder such as LS. By dialing a particular number, for instance 0, the group selector SEL rises to the top level wherein the office lines are connected. After the running-down of the dial switch the group selector commences to hunt for an idle exchange line.

The engagement of the exchange line, i. e., the set allotted to the exchange line, takes place over the *c* wire. The testing relay (not shown) of the group selector has potentially applied to it so that if the group selector rests on the contact plate of an idle set a testing circuit can be traced as follows: potential, testing relay of the group selector GW, relay C of the exchange set, earth. The testing relay switches through the speaking line so that, in the exchange set, the feed relay *Sp* may function, thus establishing with its contact *sp*₁ the loop to the exchange and for energizing over contact *sp*₁₁ a slow acting relay *V*₁. The relay C energizes over the above traced circuit and causes the energization of relay T over contact *c*_{ff}. Over contact *c*_{ff} there functions a relay X which takes care of the switching-through to the central exchange. The relay *V*₁ is a slow acting relay and is adjusted so that, during the running down of the dial switch, it does not retract, even when it is short circuited by the retraction of *sp*₁₁.

The subscriber now dials and lets the dial switch run down; consequently, the feed relay *Sp* receives the impulses and opens the loop to the exchange through the contact *sp*₁ a corresponding number of times. Dur-

ing the first retraction of the impulse relay S_p , the relay V_2 responds in known manner, this also being provided with delayed retraction and the following circuit is established: potential over retracted contact sp_{II} , relay V_2 , contact v_1 III, earth. In order to improve the impulses the relay V_2 short circuits the choke Dr_1 in the exchange loop over contact v_2 I. At the exchange set 10 there is a sequence switch St , which is advanced a step each time the relay V_2 operates. In the present case the dial switch is operated four times to send four series of impulses to complete a connection. The sequence switch St has thus been advanced by four steps until it finds itself in a position which may be defined by exchange speaking. In this position the relay F responds over: potential, rotating arm 2 of the sequence switch 15 St contact V_2 IV, relay F (winding II), contact v_1 III earth. The loop over the main exchange trunk line for holding the main exchange switches now extends by way of contacts f_{II} and choke coil Dr^2 . When the 20 called subscriber A' replies, both subscribers are in connection with each other.

In order to maintain a back call within the house, the house subscriber has to advance the sequence switch St by a further step, for 25 which purpose he has to dial once and allow the dial to run down. Preferably only one impulse is given out of course. During the running down of the dial switch, as already mentioned the relay V_2 responds, and over contact v_2 II advances the sequence switch St the required step.

After the retraction of the relay V_2 a circuit for the switching relay U is formed as follows: potential, rotary arm 2 of the sequence switch St , contact v_2 III, relay U , back contacts h_{II} , v_1 III, earth. The relay U holds itself over contact u_{II} ; it is provided with a slow-acting retraction. Through contact u_{II} the relay X is made to retract and thereby brings about the switching of the impulse contact sp_1 to the back call terminal. By the opening of the contacts x_1 and x_{III} the exchange subscriber A' is cut off but his loop is still held over the contact u_1 and choke coil Dr^2 .

The house subscriber A now hears the dial tone of the automatic house exchange, and dials the telephone number of subscriber A^2 with whom he wishes to conduct the back call. 55 In the present case the house subscriber A^2 is to be selected by a three-digit number. The sequence switch is therefore advanced three rotary steps by the time the local switches such as SEL and CONN have completed connections to the line of subscriber A^2 . In order to return to the main exchange connection, the sequence switch must be advanced again by one step, which may be done by dialing the number 1 once more.

60 In order to permit several back calls to be

made, it is necessary to again return the sequence switch into the position "exchange speaking". This is done in the following manner. As is mentioned, the relay U retracts with a slow action and therefore it keeps its contact u_{III} closed for a moment, even when the rotary arm 2 of the sequence switch has already left the contact plate. Now a temporary circuit for a relay H is closed; potential, rotating arm 2 of the sequence switch St , relay H , contacts u_{II} , h_{II} , v_1 III, earth. The relay H holds itself over its contact h_{III} , and connects the rotary magnet DM of the sequence switch St to a relay interrupter RU so that the sequence switch St is rapidly advanced until the arm of the same comes into the position "exchange speaking". In this moment the relay H retracts and stops the rotary switch. The exchange call can now be continued. As the position "exchange speaking" agrees perfectly with the condition before the back call was made, any number of such calls may be made.

Incoming traffic

The alternating ringing current from the exchange energizes the calling relay A which holds itself over its winding II and switches on the calling lamp AL . The operator at the private branch exchange operates her listening key allotted to the exchange line in the position "central office", whereby the operator's set is connected in known manner to the exchange line and the relay F is energized over winding I. The requirements of the calling main exchange subscriber, such as A' , are attended to by means of a plug S and jack J when a call to a local private branch subscriber's line, such A , is made thereby. The jack sleeve of the private branch exchange has a potential so that the relay K can respond over the c -wire of the plug S and at the same time, by short circuiting its high resistance winding II, makes the called subscriber's line busy in a well known manner.

When the called subscriber A replies the line relay S_p responds over the loop circuit formed by raising the receiver, and at contact sp_1 again closes the loop to the exchange, because through contact h_1 , the relay X , which initiated the switching-through to the exchange, is already energized. Line relay SP at contact SP^{II} again causes the energization of relay V_1 . The response of the relay V_1 causes a circuit to be formed for the relay H as follows:—potential, rotary arm 2 of the sequence switch St , position O, relay H , contact h_1 , v_1 III, earth. The relay H over contact h_{II} again connects the rotary magnet DM of the sequence switch St to the relay interrupter RU . The sequence switch rotates in the manner previously described to "exchange speaking" position. At this moment, as already described for the outgoing traffic, the relay F responds over winding II and again

transfers the exchange loop from the choke coil D_{r_1} to D_{r_2} .

The switching over to a back call now takes place in exactly the same manner as was described for outgoing traffic. The house subscriber A first dials digit No. 1 and then the number of the desired house subscriber whom he wishes to call. At the end of the conversation the return to the exchange 10 call is again made by selecting dialing digit No. 1, whereby the sequence switch is once more sent into the position "exchange speaking" by means of the relay interrupter.

Release of a call

15 When the house subscriber A hangs up his receiver the feed relay S_p retracts and over contact s_{pII} temporarily energizes the relay V_2 , short circuiting, with the same contact, the relay V_1 , which retracts with a delayed motion thereby interrupting also the circuit for the relay V_2 . Through contact v_1 I the relay interrupter LU is connected over the rotary arm 1 of the sequence switch 20 S_t to the rotary magnet DM which, in known manner is sent into the 0 position or its normal position. The winding III of the relay T lies in parallel with the rotary magnet DM. If the call was an outgoing one 25 the relay C would be short circuited by the retraction of the contact v_1 II of the relay V_1 and thereby the c-wire to the group selector would be interrupted, thus causing release. Since the relay T remains energized 30 until the sequence switch has returned to the 0 position, the exchange set remains blocked to a fresh call just as long. If the call, however, is an incoming one, the clearing lamp is lit and the operator has to withdraw the 35 plug.

40 When connection is made to a manual exchange it is desirable at the end of a call, further to block the line for about 15 seconds for the outgoing traffic, in order that the 45 central exchange operator may have time to cut off the connection. For this purpose also the sequence switch S_t may be used until the return to the 0 position is effected by a slow-acting interrupter LU. Since the relay T 50 remains energized just as long over its winding III, the desired blocking of the exchange line is achieved.

What is claimed is:

1. In an automatic telephone system, a 55 private branch exchange, a main exchange, a two-wire trunk circuit connecting said exchanges, means for establishing a talking connection over said trunk circuit in either direction, means controlled by a calling subscriber in the private branch exchange dialling a predetermined number of digits after being connected to a main exchange subscriber and without hanging up his receiver for holding the connection to the 60 main exchange subscriber and for completing 65

a connection to a desired local private branch exchange subscriber; said main exchange subscriber being excluded from the talking circuit of the last mentioned completed connection between the local subscribers, and means responsive to a subsequent dialling operation without the calling subscriber hanging up his receiver for disconnecting said other local subscriber and for again connecting with said established connection to said main exchange subscriber's line. 70

2. In a private branch exchange, a two-wire trunk circuit extending to a main exchange, means controlled by a calling subscriber for establishing a talking connection over said trunk circuit to a subscriber in the main exchange, a switch in said trunk circuit operated one step for each digit of the called number and set in main exchange speaking position at the end of the digit impulses, means responsive to subsequent impulses sent by the calling subscriber for moving said switch out of speaking position, for holding the established connection to the main exchange subscriber, and for completing a 80 talking connection to another local private branch exchange subscriber's line, and means responsive to a further subsequent impulse sent by the calling subscriber for disconnecting said other local subscriber, for reconnecting with said established connection to the main exchange subscriber's line, and for automatically causing said switch to again step to exchange talking position. 85

3. In a private branch exchange, a two-wire trunk circuit extending to a main exchange, means controlled by a calling subscriber for establishing a talking connection over said trunk circuit to a subscriber in the main exchange, a switch in said trunk circuit operated one step for each digit of the called number and set in main exchange speaking position at the end of the digit impulses, means responsive to subsequent impulses sent by the calling subscriber for moving said switch out of speaking position, for holding the established connection to the main exchange subscriber, and for completing a talking connection to another local private branch exchange subscriber's line, and means responsive to a further subsequent impulse sent by the calling subscriber for disconnecting said other local subscriber, for reconnecting with said established connection to the main exchange subscriber's line, and for automatically causing said switch to again step to exchange talking position. 100

4. In a private branch exchange, a two-wire trunk circuit extending to a main exchange, and means in said trunk circuit to enable a calling private branch exchange 105

- subscriber to, first, call a main exchange subscriber, second, complete a connection to another private branch exchange subscriber without releasing the connection to the main exchange subscriber, and, third, release the connection to the said other local private branch exchange subscriber and reconnect to the established connection to the main exchange subscriber, said means being controlled by the calling private exchange subscriber dialling predetermined digits without hanging up his receiver.
5. In a private branch exchange, a two wire trunk circuit extending to a main exchange, and means in said trunk circuit to enable a calling private branch exchange subscriber to, first, call a main exchange subscriber, second, complete a connection to another local private branch exchange subscriber without releasing the connection to the main exchange subscriber, and, third, release the connection to the said other local private branch exchange subscriber and reconnect to the established connection to the main exchange subscriber, said means comprising a sequence switch in said trunk circuit which is directly controlled by impulses generated by the calling subscriber.
6. In an automatic telephone system, a trunk line having two branches, means in said trunk line responsive to its seizure for closing a bridge across said trunk line, means responsive to impulses transmitted by a calling subscriber for interrupting said bridge to operate a train of automatic switches over the first of said branches to complete a connection to a called line, and means responsive to subsequent impulses transmitted by said calling subscriber for disconnecting said first branch from said trunk line, for holding said switches in operated position over said first branch, for connecting said trunk line to the second of said branches, and for interrupting said bridge to operate a second train of automatic switches over said second branch to complete a connection from said calling line to a second called line.
7. In an automatic telephone system, a trunk line having two branches, means in said trunk line responsive to its seizure for closing a bridge across said trunk line, means responsive to impulses transmitted by a calling subscriber for interrupting said bridge to operate a train of automatic switches over the first of said branches to complete a connection to a called line, means responsive to subsequent impulses transmitted by said calling subscriber for disconnecting said first branch from said trunk line for holding said switches in operated position over said first branch, for connecting said trunk line to the second of said branches, and for interrupting said bridge to operate a second train of automatic switches over said second branch to complete a connection from said calling line to a second

called line, and means responsive to further impulses transmitted by the calling subscriber for disconnecting said second branch from said trunk line thereby releasing the second switch train and for reconnecting said trunk line to said first branch and said first called line.

8. In an automatic telephone system, a trunk line, means controlled by a calling subscriber for operating a train of automatic switches over the two conductors of said trunk line in series to complete a connection to a called line, and means responsive to said calling subscriber dialling a predetermined number for opening both conductors of said trunk line and for closing a bridge across said conductors at a point beyond the opened section in order to hold said train of switches in operated position.

9. In an automatic telephone system, a trunk line, means controlled by a calling subscriber for operating a train of automatic switches over the two conductors of said trunk line in series to complete a connection to a called line, means responsive to said calling subscriber dialling a predetermined number for opening both conductors of said trunk line and for closing a bridge across the conductors of the outgoing section in order to hold said train of switches in operated position, and a second train of automatic switches controlled over the conductors of the other section to complete a connection from said calling line to a second called line responsive to said dialling operation.

10. In an automatic telephone system, a trunk line, means controlled by a calling subscriber for operating a train of automatic switches over the two conductors of said trunk line in series to complete a connection to a called line, means responsive to said calling subscriber dialling a predetermined number for opening both conductors of said trunk line and for closing a bridge across the conductors of the outgoing section in order to hold said train of switches in operated position, a second train of automatic switches controlled over the conductors of the other section to complete a connection from said calling line to a second called line responsive to said dialling operation, and means responsive to a subsequent dialling operation by said calling subscriber for disconnecting and releasing said second train of switches from the conductors of said other section and for reconnecting said conductors to said first train of switches.

11. In a telephone system, a trunk line having two branches, means controlled by a calling subscriber over the first of said branches for operating a train of switches to complete a connection to a called line, and means responsive to a dialling operation by said calling subscriber for operating a second train of switches over the second of said branches to

complete a connection from said calling line to a second called line, and for disconnecting the first branch from said trunk line without releasing said connection to the first called line during the time the connection to said second called line is maintained.

12. In a telephone system, a trunk line having two branches, means controlled by a calling subscriber over the first of said branches for operating a train of switches to complete a connection to a called line, means responsive to a dialling operation by said calling subscriber for operating a second train of switches over the second of said branches to complete a connection from said calling line to a second called line, and for disconnecting the first branch from said trunk line without releasing said connection to the first called line during the time the connection to said second called line is maintained, and means responsive to a subsequent dialling operation by said calling subscriber for disconnecting and releasing the connection to the second called line over the second branch and for reconnecting the calling line to said first called line connection over the first branch.

13. In an automatic telephone system, a private branch exchange, a main exchange, a trunk line connecting said exchanges, means controlled by a calling branch exchange subscriber for completing a connection over said trunk line to a main exchange subscriber's line, means controlled by said calling subscriber dialling a predetermined number of digits without hanging up his receiver for disconnecting but not releasing the connection to the main exchange subscriber and for completing a connection to a desired local private branch exchange subscriber's line.

14. In an automatic telephone system, a private branch exchange, a main exchange, a trunk line connecting said exchanges, means controlled by a calling branch exchange subscriber for completing a connection over said trunk line to a main exchange subscriber's line, means controlled by said calling subscriber dialling a predetermined number of digits without hanging up his receiver for disconnecting but not releasing the connection to the main exchange subscriber and for completing a connection to a desired local private branch exchange subscriber's line, and means responsive to a subsequent dialling operation of said calling subscriber without hanging up his receiver for disconnecting and releasing the connection to said other local subscriber's line and for connecting the calling line to said established connection to the main exchange subscriber's line.

15. In an automatic telephone system, a trunk line, means controlled by a calling subscriber over said trunk line for operating a train of automatic switches to complete a connection to a called line, means responsive to said calling subscriber dialling a predetermined number for operating a second train of automatic switches over said trunk line to complete a connection from said calling line to a second called line, and means whereby said first and second train of switches are disconnected from each other and the first train is maintained in operated position.

16. In an automatic telephone system, a trunk line, means controlled by a calling subscriber over said trunk line for operating a train of automatic switches to complete a connection to a called line, means responsive to said calling subscriber dialling a predetermined number for operating a second train of automatic switches over said trunk line to complete a connection from said calling line to a second called line, means whereby said first and second train of switches are disconnected from each other and the first train is maintained in operated position.

17. In a telephone system, a main exchange, a private branch exchange, a two way trunk line connecting said exchanges, means for completing a connection between a main exchange subscriber's line and a private branch exchange subscriber's line in either direction over said trunk line, and means responsive to a dialling operation by the private branch subscriber regardless of whether such subscriber is the calling or the called subscriber in the established connection for disconnecting the branch exchange subscriber's line from the main exchange subscriber's line without releasing the connection thereto and for completing a connection from the private branch subscriber's line to a second called line.

18. In a telephone system, a main exchange, a private branch exchange, a two way trunk line connecting said exchanges, means for completing a connection between a main exchange subscriber's line and a private branch exchange subscriber's line in either direction over said trunk line, means responsive to a dialling operation by the private branch subscriber regardless of whether such subscriber is the calling or the called subscriber in the established connection for disconnecting the branch exchange subscriber's line from the main exchange subscriber's line without releasing the connection thereto and for completing a connection from the private branch subscriber's line to a second called line, and means responsive to a subsequent dialling operation by said private branch subscriber for disconnecting and releasing the connection to the second called line and for reconnecting the private branch subscriber to the established connection to the main exchange subscriber's line.

19. In a telephone system, a main exchange, a private branch exchange, a two way trunk line connecting said exchanges, means for completing a connection between a main exchange subscriber's line and a private branch exchange subscriber's line in either direction over said trunk line, means responsive to a dialling operation by the private branch subscriber regardless of whether such subscriber is the calling or the called subscriber in the established connection for disconnecting the branch exchange subscriber's line from the main exchange subscriber's line without releasing the connection thereto and for completing a connection from the private branch subscriber's line to a second called line, and means responsive to a subsequent dialling operation by said private branch subscriber for disconnecting and releasing the connection to the second called line and for reconnecting the private branch subscriber to the established connection to the main exchange subscriber's line.

19. In a private branch exchange, a trunk line extending to a main exchange, means controlled by a calling subscriber for establishing a talking connection over said trunk line to a subscriber in the main exchange, a register in said trunk line operated one step for each digit of the called main exchange subscriber's number, and means responsive to subsequent impulses transmitted by the calling subscriber for operating said register to disconnect the calling subscriber's line from the established connection to the main exchange without releasing such connection and for completing a connection between said calling line and a second called line over a branch of said trunk line.
20. In a private branch exchange, a trunk line extending to a main exchange, means controlled by a calling subscriber for establishing a talking connection over said trunk line to a subscriber in the main exchange, a register in said trunk line operated one step for each digit of the called main exchange subscriber's number, means responsive to subsequent impulses transmitted by the calling subscriber for operating said register to disconnect the calling subscriber's line from the established connection to the main exchange without releasing such connection and for completing a connection between said calling line and a second called line over a branch of said trunk line, and means thereafter controlled by said register responsive to a subsequent digit for disconnecting and releasing the connection to the second called line and for reconnecting said calling line to the established connection to the main exchange subscriber's line.
21. In a telephone system, a trunk line having two branches, means responsive to impulses transmitted to said trunk line for completing a connection from a calling line to a called line over the first of said branches, a register associated with said trunk line operated one step for each series of impulses transmitted to said trunk line, and means controlled by said register after taking a predetermined number of steps for switching the trunk line from connection with said first branch to connection with the second of said branches in order to complete a connection from said calling line to a second called line.
22. In a telephone system, a branch exchange in which outgoing trunk connections are completed by means of automatic switches directly controlled by a branch exchange subscriber, and in which incoming trunk connections are completed by an attendant, means responsive to directive impulses transmitted by a branch exchange subscriber engaged in either an incoming or outgoing trunk connection for establishing an auxiliary connection to another branch exchange subscriber without releasing the trunk connection, and means responsive to further directive impulses transmitted by the branch exchange subscriber for releasing said auxiliary connection and for reestablishing the trunk connection.
23. In a telephone system, a branch exchange in which outgoing trunk connections to main-exchange subscribers are completed by means of automatic switches directly controlled by a branch-exchange subscriber and in which incoming trunk connections from main-exchange subscribers are completed by an attendant, means responsive to directive impulses transmitted by a branch-exchange subscriber engaged in either an incoming or outgoing trunk connection for establishing an auxiliary connection to another branch-exchange subscriber from which connection the main-exchange subscriber is excluded, and means responsive to further directive impulses transmitted by the branch-exchange subscriber for releasing said auxiliary connection and for reestablishing the trunk connection.
24. In a telephone system, a trunk line having two branches adapted to be connected to the trunk line alternately, means for transmitting series of digit impulses over the trunk line to establish separate connections to called lines over said branches, and an auxiliary switch operated one step for each series of impulses transmitted over the trunk line for controlling the connection of said branches to the trunk line.
25. In a telephone system, a trunk line having two branches adapted to be connected up one at a time, means for transmitting groups of digit impulses over the trunk line, each of said groups representing the digits of a called-subscriber's number followed by an additional digit, means for repeating the called-number digits over the particular branch connected, an auxiliary switch operated one step for each digit transmitted over the trunk line, and means controlled by the switch on operating in response to the additional digit impulses for connecting up the previously-disconnected branch.
26. In a telephone system, a trunk line having two branches, automatic switches, a line relay controlled over the trunk line for repeating digit impulses over one of said branches to operate certain of said switches to extend a connection to a called line, an auxiliary switch operated one step responsive to each series of impulses representing a digit of a called number, and means controlled by said switch when operated to a predetermined position for adapting said relay to repeat impulses over the other of said branches to operate certain other of said automatic switches to extend a connection to a second called line and for maintaining said first connection intact.
27. In a telephone system, a trunk line terminating in a branch exchange, means for

- transmitting digit impulses over the trunk line to complete outgoing calls to called subscribers, means for extending incoming calls over the trunk line to subscribers in the
5 branch exchange, an auxiliary switch associated with the trunk line, a speaking position for said switch to which the wipers of the switch are advanced one step at a time responsive to successive digits transmitted
10 over the trunk line to complete an outgoing call, and circuit connections for automatically advancing the wipers of the switch to speaking position or incoming calls over the trunk line.
- 15 28. In a telephone system, a trunk line terminating in a branch exchange, means for transmitting digit impulses over the trunk line to complete outgoing calls to called subscribers, means for extending incoming calls
20 over the trunk line to subscribers in the branch exchange, an auxiliary switch associated with the trunk line, a home position in which the wipers of the switch normally stand, a speaking position to which the wipers of the switch are advanced one step at
25 a time in response to the digits of a called number on outgoing calls, circuit connections for automatically advancing the wipers of the switch to speaking position on incoming
30 calls, and circuit connections for returning the wipers of the switch to home position responsive to the termination of either an outgoing or an incoming call.

In witness whereof, I hereunto subscribe
35 my name this 19th day of September, A. D.
1927.

HANS TATZL.
